UNITED STATES PATENT OFFICE.

RICHARD SEDGWICK, OF RICHMOND, INDIANA.

AUTOMATIC INDICATOR FOR TELEPHONES.

No. 903,898.

Specification of Letters Patent.

Patented Nov. 17, 1908.

Application filed July 29, 1907. Serial No. 386,139.

To all whom it may concern:

Be it known that I, RICHARD SEDGWICK, a citizen of the United States, residing in the city of Richmond, county of Wayne, and State of Indiana, have produced a new and useful Invention, entitled Automatic Indicators for Telephones, of which the following is a full, clear, and accurate specification and exposition, being such as will enable others skilled in the art to which the invention pertains to make and use the same with exactitude.

The invention relates, broadly, to an automatic call-indicator for automatic telephones or the like.

The object of my invention, briefly stated, is to provide an automatic indicator for automatic telephones, which will be easily attached to or made a part of the telephone-subscriber's set; which will be simple in construction; automatic in operation; will not detract from the appearance of the telephone with which it is employed; will not consume additional time of the person using it, or add to the labor or difficulties of manipulation; can be employed with any one, a portion of, or all of the telephones in an automatic system, and without the necessity of having all of the telephones of a certain system so equipped; will add materially to the efficiency of the telephones on which it is employed; and which can be manufactured and installed at a comparatively low price.

More specifically stated, my object is to provide an automatic indicator for telephones, which will automatically bring into the view of the user of the telephone the numerals indicative of the telephone he is attempting to call, bringing the figures into view progressively as they are indicated, in the usual manner, by the user employing the ordinary automatic-telephone, whereby a mistake made by the user (which might not be observed by him without my invention) may be detected by him before he rings the call, thereby enabling him to correct his error without bother to the subscriber he has indicated by mistake, and also saving time and embarrassment to himself.

A further particular object is to provide an automatic indicator for automatic telephones which will exhibit to the user of the telephone or which it is employed the individual

numeral of the telephone he has called, or is attempting to call, and which will continue to display the last number called, unless intentionally displaced, until such time as the commencement of a new call to be made on the same telephone; and at the commencement of such new call the prior number will automatically disappear.

Other objects and particular advantages of my invention will present themselves in the course of this specification, will be found in the drawings forming a part hereof, and the principles thereof, the parts which are new, and the various combination will be set forth in the appended claims.

One manner of carrying out the principles of my invention, and that which in practice I have found to be the most practical, is shown most clearly in the accompanying drawings, in which—

Figure 1 is a front view of an ordinary automatic telephone equipped with my invention. Fig. 2 is a rear view of the rotative-dial. Fig. 3 is a face view of the concentric rings forming a part of my invention. Fig. 4 is a vertical sectional view, as taken on the line $x-x$ of Fig. 1. Fig. 5 is a front elevation of the telephone case showing front view of my inner disk attached thereto. Fig. 6 is a rear elevation of the parts shown in Fig. 3. Fig. 7 is a rear elevation of the inner disk shown in Fig. 5. Fig. 8 is a front elevation of the telephone case, in which view the dial and the inner disk and also the concentric springs and rings are removed, this view showing the means for rotating the dial back to normal and also the means actuating the release of the concentric rings. Fig. 9 is a face view of the concentric rings, being the same as Fig. 3 except that the rings have been rotated to the positions they would occupy when displaying the number 1359. Fig. 10 is a perspective view of the rear sides of the assembled concentric rings, in which the springs are removed from their respective channels. Fig. 11 is a detail cross section, as taken on the line $y-y$ of Fig. 7, and Fig. 12 is a detail view showing the incline in elevation.

Similar reference characters designate like parts throughout the several views of the three sheets of drawings.

Before taking up the description of my invention it is necessary, in order to have a full understanding thereof, to refer, briefly, to the construction and operation of the mechanism to which my invention may be connected, which is shown in Fig. 1, and may be stated as follows: In ordinary automatic (so called) telephone systems there is provided for each subscriber a stand (or wall cabinet) A, carrying the telephone-case C containing the various mechanisms and the transmitter B as shown. Extending out to the left from the case C is a lever D which extends into the case C where it is pivoted and provided with a spring for causing the outer end thereof to remain, normally, at its highest point. On the outer end portion of the lever D is a prong, or hook, for suspending the receiver E, which receiver when suspended therefrom holds the lever D down to its lowest point, as in Fig. 1. Rotatively mounted over the face of the case C is the numerating-dial F. Permanently secured to the case C and extending out therefrom, near the lowest position of the periphery, is the stop G. Said dial F is secured to the stem H by the screw I, said stem being controlled as to its rotation in one direction by the flat coil-spring U which is located in the face of the front of the case C, as shown in Fig. 8, which spring is adapted to retain the dial F, normally, to the left in the position shown in Fig. 1, but allowing the dial F to be manually rotated to the right, against the resiliency of said spring U, to one-half the circumference of the dial, which on being released will be rotated back to normal by said spring U. In this instance there are formed through one side of the dial F, near the edge thereof, eleven finger apertures, each being designated by its permanent title, as: "Long Distance, 0, 9, 8, 7, 6, 5, 4, 3, 2, 1," which extend from right to left in the order given, and located in the arc of a circle. By placing one's finger in either of said apertures, and one's thumb of the same hand against the stop G, it is evident that the dial may be rotated to the right until the finger of the hand engages the stop G which will bring the character opposite said aperture into alinement with said stop, after which the dial is released and returns to its normal position, and then another character is brought into alinement with the stop G as before, and so on until all of the figures composing the number desired have been brought into alinement with said stop. By the above it is apparent that any number or combination of figures or other characters may be assembled up to the limits of the telephone. After each combination of figures has been brought into alinement with said stop then the calling party or user has only to press the push-button J 65 which will ring the bell of the subscriber

whose number has just been assembled. It should also be understood that before beginning the arrangement of the numerals for a certain number, that is before instituting the call, the user first removes the receiver E 70 from the lever or hook D.

In order to accommodate the telephone, just described, to the employment of my invention I have only made the stem H slightly longer than ordinary, that I may position 75 the dial F slightly farther from the face of the case C to give room for my mechanism therebetween, as shown in Fig. 4; I provide the dial F with a slot F^a formed there-through, as shown in Figs. 1 and 2; and I 80 provide the inner end of the lever D with an outwardly extending pintle 81 to provide a trip as will hereinafter be described.

Referring now, more particularly, to my specific construction, I will describe the several parts and the construction and the several operations thereof as briefly and as compactly as I may.

The numeral 10 denotes a disk which is connected to and extends over the central 90 portion of the front of the case C, and is located a slight distance therefrom where it is secured by the screws 11, 12 and 13, as shown in Figs. 4 and 5, the reverse side of said disk 10 being shown in Fig. 7. A central aperture is formed through said disk in which operates the stem H. Located on the rear face of the disk 10 are four springs 14, 15, 16 and 17 which lie parallel with each other and flat against the disk, as shown 95 in Figs. 7 and 11, and having one end of each permanently secured to the disk, from where they extend upwardly and outwardly slightly beyond the medial horizontal line across the disk, on which line is a forwardly 100 extending stud carried by each spring, said studs are designated by the numerals 18, 19, 20 and 21, respectively, and they are shown in said Figs. 7 and 11. Apertures are formed through the disk, one for each of 110 said studs and said studs extend through said apertures, as shown in Figs. 5 and 11, and, when the springs are flat against the disk, said studs project slightly outward beyond the face of the disk 10, as shown in 115 Fig. 11, for the purpose presently appearing. The blade 22^a of the lever 22, is adapted to be slid under the free ends of said springs in order to draw the studs inward by which their protruding end portions may be made flush with the outer face of the disk 10, this by reason of the portions of said studs which may protrude beyond the face of the dial 10 being equal, substantially, to the thickness of said blade.

The numerals 23, 24, 25 and 26 designate small eyes, or hooks, which are secured to the face of the disk 10, located on a line radiating from the center to the periphery thereof, in which eyes are securable one end 125

each of the respective relatively long helical springs 27, 28, 29 and 30, which are shown in Figs. 4 and 6.

The numerals 31, 32, 33 and 34 denote pins or stops which are permanently secured in and rise from the face of the disk 10, whose purpose will hereinafter be made to appear, these stops are located in a line with, but are located on the opposite side of the face 10 of said disk from that of said hooks 23, 24, 25 and 26.

Permanently secured in and rising from the face of the disk 10 and located on the left-hand side thereof, are three rows of small studs or guides, which are designated as follows: The studs of the outer row are designated by the numerals 35, 36, 37, 38, 39 and 40; that of the center row by numerals 41, 42, 43, 44, 45 and 46; and that of the inner row by numerals 47, 48, 49, 50, 51 and 52, the three rows being arranged concentric with each other in arcs of circles having the center of the disk as a common center and following the curvature of the periphery of the disk. Said studs are employed as guides or bearings for the concentric rings, which will hereinafter be described, their function being to prevent frictional contact between said rings and allowing the rings to rotate 30 independent of each other.

The rings referred to immediately above are designated by the numerals 53, 54, 55 and 56, each of which is formed with an inwardly projecting flange which extends 35 from the inner edge thereof whereby they appear L-shaped in cross section, as shown in Fig. 3. Said rings are so constructed as to nest together as shown in Figs. 3, 4 and 6, forming collectively a smooth face in front, 40 and forming concentric channels which open to the rear as indicated, in which channels are contained the respective helical springs 27, 28, 29 and 30, as shown in Figs. 4 and 6. Posts or studs 77, 78, 79 and 80 are secured 45 to the respective rings and extend back through their respective channels to points equal to the depth of the channels, that is to say,—even with the rear edge of the flanges of the rings. To said posts are connected one end each of the respective springs 27, 28, 29 and 30, as indicated in Fig. 6.

Referring now to the rear side of the dial F, as shown in Fig. 2: The numeral 57 denotes a pawl frictionally pivoted, by the rivet 58, to the rear face of said dial at a point to the left of a vertical line thereacross. Said pawl is provided with a shoulder 57^a near the outer end of its longer portion, and a hook 57^b extends from one side of 50 said shoulder over and beyond the shoulder, with its inner edge inclining at an angle slightly outward from the shoulder, as shown in Fig. 2. The numeral 59 designates a stop, secured to the back of the dial F, against 55 which said pawl may engage when being

turned outward in order to prevent the pawl from turning beyond the point necessary for it to engage the pin 60. It should be understood that the pawl 57 is so mounted by the pivot therefor that it turns only by the engagement therewith of some other part, by which it is adapted to remain at any point where left after being moved by some other part of the mechanism.

Referring again to Fig. 3 it will be noticed 75 that rising from the face of each of the rings 53, 54, 55 and 56 is a pin, which pins are denoted by numerals 60, 61, 62 and 63 respectively, which when the rings are in their normal positions as shown in Fig. 3, should 80 be arranged in the arc of a circle with the rivet 58 as a center.

Secured to and rising from the front of the case C, located a little to the left of a vertical line through the center of the case, 85 and immediately outside the periphery of the disk 10, with its point rising almost to the height of the ring 53, located on the lower portion of the case, and with the incline thereof sloping upwards from the left to the 90 right, is the incline 64, shown in Figs. 5, 8 and 12, whose purpose will hereinafter appear.

Secured to the underside of the ring 53, at a point somewhat to the right of the pin 60, 95 and extending outward even with and then following the curvature of the periphery of the ring 53, is a spring arm 65, which terminates at a point slightly short of the vertical central line which passes across said 100 rings, when the rings are in normal position as shown in Figs. 3 and 6. A portion of the free end of the arm 65 is given a quarter twist in order to provide a shoulder for engaging the arm 57^c of the pawl 57, the purpose of which will hereinafter be explained. Disposed on the face of each of the rings 53, 54, 55 and 56 are the figures "1, 2, 3, 4, 5, 6, 7, 8, 9, 0", arranged progressively in proper sequence and an equal distance apart, 105 beginning one space from the respective pins 60, 61, 62 and 63 and extending to the left to near the central horizontal line of the rings, as shown in Fig. 3. It should be understood that said characters may be 110 variously changed as desired, and that they may be attached in position in any manner.

The lever 22 above referred to, in addition to having the blade 22^a, is provided with a tooth 22^b which extends inwardly parallel 120 with said blade but it is bent back, that is offset near its juncture, in order not to touch the springs 14, 15, 16 and 17, but it is adapted to be engaged by the pintle 81 which projects out from the inner end of the lever D. 125 Also extending outward from said lever 22 is a finger 22^c, and at the base of said finger there is formed a flat face or shoulder, which in fact is the body of said lever 22. The numeral 66 denotes a spring which is secured at 30

one end by the screw 12 with its free end held in contact with said shoulder 22^a by the pin 67, the latter being secured to the case C. The numeral 68 denotes a finger permanently secured to the rear face of the dial F, shown in Fig. 2, which is adapted to engage the finger 22^c, for the purpose which will hereinafter be set forth.

Operation: Suppose, now, for instance, 10 that the use of the telephone equipped with my invention predilects to call another party whose telephone number is 1359, or any other number for that matter: He first removes the receiver E from the hook, or 15 lever D; he will then place his finger in the aperture opposite "1" on the dial and turn the dial until his finger engages the stop G; he will then release the dial allowing it to swing back to its normal position, which will 20 expose the figure "1", on the face of the ring 53, through the slot F^a. He then places his finger in the aperture opposite the figure "3" on the dial, then turning the dial as before until his finger engages the stop, and 25 then after the dial is released and swings back to normal the figure "3", of the ring 54, will appear immediately to the right of the previously positioned figure "1". In 30 like manner the figures "5" and "9" of the respective rings 55 and 56 are exposed through said slot by the operation of the dial as before set forth, exposing successively said figures to the right of the previously arranged figures. By the above it is 35 apparent that the figures appearing through said slot will verify the correctness of the user's operations in manipulating the dial. If at this point the user, which may be 40 termed the "calling party", should discover that he had made a mistake in arranging his number then he will hang up his receiver, and on taking down the receiver again the arrangement is such that all of the figures which have been appearing through the slot 45 F^a will instantly disappear from view. On the other hand if the calling party finds that the number appearing through said slot is correct then he will press the button J thereby signaling the party whose number 50 he has just arranged. If the party signaled is busy, or after finishing the conversation with the called party, the user will hang up his receiver, but it should be noted that the number of the party last called, that is to 55 say Number 1359, will continue to appear through the slot F^a, and will remain so exposed until the receiver of that telephone is again taken down. The removal of the receiver E from its hook on the telephone will 60 cause the number "1359" to instantly disappear, showing the slot blank and ready for a new number to be assembled.

It is obvious that if the user calls a certain number and that telephone happens to be 65 busy, then the user hangs up the receiver,

and if he desires to call the same party again, before another call is made on his telephone, then the number of the party he desires will be in view through said slot, which of course will be a convenience.

The mechanism of my invention above described, taken in connection with the system as set forth, is adapted to produce the results as stated, the several operations being substantially as follows: Suppose the several 70 parts to be in normal position, as in Figs. 2, 3, 4, 5, 6 and 10, and the user desires to call the number 1359 and on going to his telephone he finds either that space of the slot F^a is blank, or that it is occupied by the last 75 number that has been called on that telephone, and on taking down his receiver E the number, if there is one appearing through the slot, will immediately disappear from sight, this by reason of the pintle 81 on the inner end of the lever D impinging the tooth 22^b thereby turning the lever 22 and causing its blade 22^c to slide under the springs 14, 15, 16 and 17, to the position shown in dotted lines in Fig. 5, which of course will draw 80 the studs 18, 19, 20 and 21 back with their ends flush with the face of the disk 10 and consequently from engagement with the shoulders of the teeth which are formed in the rearwardly extending flanges of the respective rings 53, 54, 55 and 56, said teeth being shown in Fig. 10, thereby allowing the respective springs 27, 28, 29 and 30, which would then be at tension, to rotatively draw 85 their respective ring to the left until the 90 studs 77, 78, 79 and 80 impinge the respective stops 31, 32, 33 and 34 which will retain the rings at normal. As the ring 53 returns 95 it will in transit cause the free end of the spring-arm 65 carried thereby to engage the 100 arm 57^c and return the pawl 57 to the normal position shown in Fig. 2.

The next step will be for the user to assemble the number of the telephone he desires to call: First, he will turn the dial F to bring 110 the figure "1" thereon even with the stop G, the first part of this movement will cause the finger 68 to strike the finger 22^c thereby throwing up the blade 22^c out of engagement with the springs 18, 19, 20 and 21, 115 where it will be retained by reason of the spring 66 pressing squarely on the shoulder 22^d. The last mentioned movement of the dial will also cause the shoulder 57^a to engage 120 the pin 60, thereby carrying along with the dial the outer ring 53 to a point where the figure "1" of the ring 53 will be opposite the slot F^a, that is after the dial has 125 returned to its normal position, at which point said ring and the figure thereon will be retained by reason of the stud 21 engaging, ratchet-like, with one of the teeth on the flange of said ring. Immediately following the positioning of the first figure, "1", the dial is released, and as it swings back to 130

normal the pin 60 will impinge the hook 57^b and, by reason of the inclination of said hook, the pin 60 will not be engaged thereby and as the pin is not movable it is evident that the hook 57^b will slide off said pin thereby moving the pawl 57. The length of the hook 57^b is such that the pawl will be moved centerward the requisite distance in which on the second rotation of the dial to the right the shoulder 57^a will engage the pin 61. Said pawl 57 is held in the position, to which it is or may be moved by said pins, by reason of its frictional engagement by the rivet 58 above referred to. It is apparent that the spring 65 is, by the above, moved with the ring 53 whereby it will not influence the pawl 57 during the setting of the other remaining rings. Secondly,—the user now places his finger in the aperture opposite the figure "3" and revolves the dial as before until his finger engages the stop G, in this movement the shoulder 57^a of the pawl 57 will engage the pin 61, by reason of that above stated, thereby rotating along with the dial the ring 54, which when the rotation of the dial has reached the point where the figure "3" on the dial is even with the stop G it will have carried the ring 54 therewith to a point where the figure "3" of the ring 54 will be directly opposite the aperture F^a and therefore immediately to the right of the previously positioned figure "1" of the ring 53. Now as the dial F is released the stud 19 will be pressed by its spring 15 into one of the notches in the flange of the ring 54 thereby retaining the ring 54 in the position shown in Fig. 9, and as the dial continues to rotate back the pin 61 will strike the hook 57^b thereby moving the pawl centerward one space as before, to the position whereby the shoulder 57^a thereof will engage the pin 62 on the next forward rotation of the dial. As the dial continues to move back towards its normal position it is apparent that the finger 68 will pass over or to the side of but can not engage with the finger 22^c, on account of the angle at which said finger is disposed during these movements, it being removed out of the path of the finger 68 where it is retained by the spring 66. Third,—the user now places his finger in the aperture opposite the numeral "5" of the dial and then rotates the dial to the right until said figure "5" is in alignment with the stop G, during this movement the shoulder 57^a of the pawl has engaged the pin 62 thereby rotating the ring 55 therewith until the figure "5" thereon is opposite the slot F^a, and in alignment with the prior disposed figures "1" and "3". Now if the dial F be released it will of itself rotate back to normal, that is to the position shown in Fig. 1, and in this last movement of the dial the pin 62 will strike the hook 57^b and move the pawl 57 centerward to the position for the shoulder 57^a to engage the pin 63 on the next forward movement of the dial. Fourth,—in this movement the operator will, as before, bring the figure "9" of the dial on a line with the stop G which manifestly will cause the shoulder 57^a to have engaged the pin 63 thereby rotating the ring 56 therewith until the figure "9" of the ring 56 is opposite the slot F^a and in alignment with the previously positioned figures where it is retained by the stud 21 engaging in one of the notches on the flange of said ring 56. The dial is then released and rotates back to normal, which will allow the numerals "1359" to appear through the aperture F^a, as in Fig. 1, the rings being retained in the positions shown in Fig. 9. Now if the user will press the button J he will, by instrumentalities immaterial to an understanding of this invention, cause the bell to ring on the telephone contained in that system which has the number "1359". After ringing the bell on the telephone of the called-party the called-party is signaled to his telephone for conversation with the calling-party, and during such conversation the number "1359" will be in view of the calling-party. Now suppose the conversation to be finished, then the calling-party hangs up his receiver E, but the number "1359" continues in sight as before and in fact will continue to be in sight until the user again takes down his receiver. Now as the receiver is taken from the arm D the arm springs up to its highest point thereby moving the pintle 81 downward into contact with the tooth 22^b, thereby drawing the blade 22^a under the springs 14, 15, 16 and 17 which will draw the studs 18, 19, 20 and 21 back flush with the disk 10 thereby releasing all of the rings 53, 54, 55 and 56 and allowing their respective springs to return them, smartly, back to their normal position. The first movement of rotating the dial F for a new number will cause the finger 68 to engage the finger 22^c thereby turning the pawl 22 and removing the blade 22^a from engagement with the springs 14, 15, 16 and 17 and allowing means for the new number to be retained in position as that of the number shown in Figs. 1 and 9.

It is apparent that my invention will operate equally well to exhibit numbers of one figure, as well as numbers of two or three figures, or as numbers of four figures as described, a number of one figure operates in the same manner as a number of four figures. It is also apparent that a greater number of rings, or number of rows of figures, or other characters, may be employed in order to compose numbers of more than four figures or letters, or figures and letters, if desired.

I desire that it be understood that various changes and modifications may be made in the details of construction without departing

from the spirit or sacrificing any of the advantages of this invention, my intention being to show and describe a specific construction but to claim broadly the combination 5 of a sight-indicator operating automatically with a so-called automatic telephone or the like.

Having now fully shown and described my invention and its intention, operation and its 10 relation to other devices, what I claim and desire to secure by Letters Patent of the United States, is—

1. A mechanism of the character set forth, a plurality of concentric rings each carrying 15 on its face a series of figures or other characters, a rotative dial operative over and concentric with said rings and having a sight aperture therethrough through which a portion of each of said rings may be seen, 20 means whereby as the dial is rotated in one direction one of said rings will rotate therewith and be locked at limit of movement in that direction until the commencement of a new call regardless of the movements 25 of the dial during the call then instituted.

2. A mechanism of the character set forth comprising an automatic telephone, a rotative dial carried by the telephone, a set of 30 figures located on the dial, a plurality of concentric rings located between the telephone and the dial, a set of figures located on the face of each of said rings, which sets of figures correspond with each other and with the 35 figures located on the dial, said dial being located over and concentric with said rings and having a sight aperture therethrough through which a portion of the face of each of said rings may be seen, means whereby as 40 the dial is rotated to denote a number to be called on the telephone said rings will be rotated to positions such as will cause the figures thereon to appear through said aperture in the dial to form the same number as that 45 arranged by the operator with the figures on the dial of the telephone, and means for retaining the same number in position until a new call is instituted on the same telephone.

3. In combination with an automatic telephone or the like, an indicator mechanism 50 for automatically bringing into the view of the calling-party the number of the telephone he has designated, and means for automatically returning the indicator mechanism to 55 normal on the commencement of a new call.

4. A mechanism of the character set forth to operate in connection with automatic telephones or the like, a plurality of independent concentric rings each having a smooth 60 face all of said faces being in alinement with and adjoining each other, a plurality of figures or the like disposed on each of said faces which figures correspond to the figures or the like located on the telephone dial, means for 65 automatically bringing into the view of the

operator a figure from one or more of said rings to form the number of the telephone to be called, and means for releasing said rings automatically by the commencement of a new call on the telephone on which said number 70 is displayed.

5. In combination with an automatic telephone, an indicator carried thereby having characters, means for assembling said characters to designate any one of the telephones 75 in the system, means for alining said characters automatically whereby they will appear progressively as the user designates the telephone to be called, and means for retaining the characters, representing the telephone called, in view of the calling party until the commencement of a new call, then to be released automatically.

6. In combination with an automatic telephone, a mechanism of the character set forth 80 comprising means for automatically displaying a plurality of characters progressively which characters correspond with the characters designated by the calling party on the automatic telephone, means for retaining the 90 characters thus designated in view of the calling party until the commencement of a new call on the same telephone which last movement will allow the prior arranged characters to automatically disappear from 95 view.

7. In combination with an automatic telephone having means for preintimating the telephone to be signaled, a mechanism in connection therewith for automatically displaying to the calling-party the characters in progressive succession corresponding to the characters denoting the telephone to be signaled, means for retaining such characters in displayed position until the commencement of a new call, and means whereby such characters are automatically displaced 100 on the commencement of a new call.

8. In combination with an automatic telephone having means for intimating the telephone in the same system to be signaled, a mechanism for automatically displaying to the calling-party the characters in progressive succession corresponding to the characters denoting the telephone to be signaled, 110 and means for retaining such characters in displayed position until the commencement of a new call.

9. In combination with an automatic telephone for electing, step-by-step, a plurality 120 of characters forming the number of the telephone to be called, means for automatically displaying to the actuator the characters he has indicated, means for disbanding the characters comprising the number in 125 sight, either at the will of the said party or automatically when the receiver of the telephone on which they are displayed is removed preparatory to a new call to be made on the same telephone.

10. A mechanism of the character described, to operate in connection with automatic telephones, a plurality of concentric rings each carrying on its face a plurality of figures or the like, means for bringing into alinement with each other a figure from each of said rings to form the complete number of the telephone to be called, said means being operable automatically by the assembling 5 of the number in the usual manner, and means for releasing said rings automatically by the commencement of a new call on the telephone on which said number is displayed.
15. 11. In combination with an automatic telephone system having a plurality of individual telephones each provided with its particular call-number and each having means for intimating the call-number of each of 20 the other telephones in that system, means connected to either, or all, of the telephones in the system for automatically displaying to the calling-party the call-number of the telephone he intimates, and means for continuing the display of said call-number, unless intentionally displaced at the telephone on which it originated, until a new call is instituted.
25. 12. In combination with an automatic telephone system or the like having a plurality of individual telephones provided with an indicative number composed of a plurality of figures, and each having means for intimating, one at a time, the figures comprising the number of the telephone which it is desired to call, means connected with each telephone for bringing into the view of the calling-party the figures, successively, composing the number of the telephone intimated, means for maintaining in view of the calling-party the number of the telephone so intimated, and means for automatically causing said numbers to disappear at the first operation of instituting a new 30 call from the telephone on which they are displayed.
35. 13. In combination with an automatic telephone system or the like having a plurality of individual telephones provided with an individual number, and each having means for intimating the number of the telephone that it is desired to call, means connected with each telephone for bringing into the view of the calling-party the number of the telephone he is intimating, means for maintaining in view of the calling-party the number of the telephone intimated, and means for automatically causing said number to disappear upon the first operation of 40 instituting a new call.
45. 14. In a non-electric sight indicator for automatic telephones, a plurality of concentric rows of figures adapted to be automatically arranged to form numbers to be composed of a plural number of figures, means 45 for selecting one figure from each of said rows and arranging them in alinement with each other, and means whereby all of said figures are released automatically and returned to their normal position at the commencement of a new call.
50. 15. In a mechanical sight indicator for automatic telephones, a plurality of circular rows of figures adapted to be automatically arranged to form either one of the numbers 55 capable of being formed with the number of rows of figures employed by the telephone-dial, means for holding the assembled number in position until the commencement of a new call, and means for returning said figures to normal position when the telephone hook is again released, all substantially as set forth.
55. 16. In combination with an automatic telephone having a rotative dial for arranging 60 the number of the telephone to be called, an automatically operable indicator comprising a plurality of identical rows of figures arranged parallel and concentric and on same plane with each other, means for operating each of said rows of figures independent of each other whereby either of the figures of each row may be brought into alinement with each of the figures of the other rows, means whereby only the selected figures may be brought into view to indicate the telephone selected by the operator of the telephone on which the indicator is located, and means for automatically retaining the assembled numbers in position until the commencement of a new call.
60. 17. In combination with an automatic telephone, an indicator actuated automatically thereby and having means for bringing to the view of the calling party the number of the telephone to be signaled, means for retaining the number indicated in position until the commencement of a new call, a plurality of independent sets of movable figures, and means whereby the several figures comprising the number called will be returned to their normal position at the commencement of a new call.
65. 18. As a new article of manufacture, in combination with a telephone or the like having a rotative number instituting dial and a receiver lever, an indicator having means for indicating automatically the number instituted by the operation of said dial, and for indicating each character progressively as it is instituted, and means for returning the character or characters automatically to their normal position at the commencement of a new call on the same telephone.
70. 19. An indicator adapted to be employed in connection with an automatic telephone having a rotative dial, a plurality of concentric rings nested together and operating within and around and independent of each other, each having an outer face, all of which 75

faces are on the same plane, and each containing on its face the same characters as those contained on the telephone dial, means for selecting the characters and for bringing the characters thus selected into alinement with each other where they may be seen by the operator as a single integer, the selection of said characters being accomplished automatically by the rotation of the telephone dial and corresponding to the characters indicated by said dial, all substantially as specified.

20. In combination with an automatic telephone having a rotative dial containing a series of figures and having an aperture therethrough, an indicator mechanism located between said dial and the telephone case and comprising a series of concentric rings nested together with their faces presenting a plain unbroken front, the face of each of said rings containing a series of figures corresponding to the figures on said dial, pins extending out from the face of each of said rings, a pawl pivoted to the back of said dial and adapted to actuate successively each of said rings in order to bring the figures thereon, corresponding with the figures indicated by the dial, opposite to said aperture in the dial when the dial is in normal position, means for retaining the figures thus appearing in said aperture in position until the commencement of a new call on that telephone, and means for releasing all of said rings automatically when the telephone receiver is taken from its hook, and a spring contained in each of said rings for returning the rings to their normal position after being released.

21. In combination with a system of electrical communication having means for electrically selecting the instrument to be communicated with, and means for signaling such instrument after being selected, mechanical means operated automatically by the selecting means for exhibiting to the operator the instrument he has selected before he has instituted the operation of signaling the selected instrument, means whereby the exhibit thus shown may not be changed except by the commencement of a new selection on the same instrument.

22. An indicator comprising a series of concentric rings located on a common plane, means for rotating each of said rings independent of the others, comprising a pawl adapted first to engage the outer ring and then progressively each of the succeeding rings, means for returning the pawl to normal after having rotated one or more of said rings, means for retaining each of said rings at the point to which it has been

moved by the pawl, means for automatically releasing at one time all of the rings which have been moved by the pawl, and springs for returning each of the rings to its normal position at the commencement of a new call or at the will of the operator.

23. The improvements in telephony, which consist of a movable manually operable means for selecting the number of the telephone to be called, automatic means for progressively denoting to the operator each of the characters selected, means for retaining the characters comprising the number selected in alinement with each other and on same plane until the commencement of a new call, and means for automatically releasing all of the characters synchronously at the first operation of the commencement of a new selection.

24. In combination with an automatic telephone having a numerating-dial rotatably mounted thereon, a purely mechanical mechanism located in the rear of said dial and operative automatically in one direction thereby for bringing to the view of the operator the characters he has indicated by the rotations of said dial, means for retaining in view of the operator the characters so intimated until the commencement of a new call on the same telephone, unless intentionally displaced, and means for withdrawing the characters indicated from view automatically at the commencement of a new call on the same telephone.

25. In combination with an automatic telephone having a vertically operable receiver hook and a rotative dial, a mechanical indicator connected thereto and comprising a series of concentric rings nested together and located between the telephone case and the dial, means for retaining said rings in rotative position to operate independent of each other, a spring for each of said rings to normally hold the rings out of operative position, means for bringing each of said rings to operative position, successively, by the rotation of said dial in one direction, means for holding each of said rings in operative position independent of said dial, and means for releasing all of the rings, which have been brought to operative position, at one time and allowing them to rotate smartly back to normal on the first operation of a new call.

In testimony whereof I have hereunto signed my name in the presence of two subscribing witnesses.

RICHARD SEDGWICK.
